UNITED STATES PATENT OFFICE

JOHN MITCHELL, OF CLINTON, INDIANA, ASSIGNOR TO CHARCOLITE CORPORATION, OF CLINTON, INDIANA, A CORPORATION OF INDIANA

APPARATUS FOR CARBONIZING COAL

Application filed August 7, 1925. Serial No. 48,756.

This invention relates to the carbonization or coking of coal, and its principal object is to provide an improved apparatus whereby a uniform product of high quality may be produced in a simple, economical and efficient manner.

More specifically, this invention relates to improvements in apparatus for coking coal by placing the same in a heat conductive container immersed in a bath of fused salts, in accordance with the broad disclosure made in prior applications of Richard Lee Rodgers, Serial No. 539,361, filed February 27, 1922, and Serial No. 591,008, filed September 28, 1922, and this invention may be considered an improvement thereof with especial reference to the construction of the apparatus used in carrying out the process.

The invention may best be understood by reference to the accompanying drawings, in which

Figure 1 is a vertical sectional view of a carbonizing unit taken on the broken line 1—1 of Figure 2;

Figure 2 is a plan sectional view of the unit shown in Figure 1, taken on line 2—2 of Figure 1;

Figure 3 is a transverse sectional view taken on line 3—3 of Figure 2;

Figure 4 is a detail view of a coking element with parts broken away;

Figure 5 is a top view of the coking element shown in Figure 4;

Figure 6 is a bottom view of the coking element shown in Figure 4;

Figure 7 is a view in side elevation of a portion of the apparatus.

The essential operating parts of the structure selected for illustrative purposes, may be seen in Figure 1 wherein is shown a carbonizing section 10 at the upper portion of the structure and discharge smothering and cooling pits 11 at the lower part of the structure.

The important elements of the carbonizing section may be first described after which the structure as a whole will be described.

The carbonizing section 10 has a battery of carbonizing containers or elements 12—12 preferably mounted in batteries or groups. In the form shown, four groups of five such

containers are shown, as appears in Figure 2. Since these four groups are similar, a description of one will suffice for understanding them all.

Referring to the group of five containers shown in the lower left-hand corner of the structure in Figure 2, each of the containers is long and narrow and is arranged vertically of the carbonizing section 10. Details of each of such containers are shown in Figure 4, from which it will be seen that they are built up of an outer cylindrical casing 15 and an inner cylindrical casing 16 spaced therefrom, said casings being supported at their lower ends on a base member 17 and at their upper end in a cap member 18. The cylindrical members 15 and 16 are preferably made of metal capable of resisting heat of fairly high temperature, such as are used in the process, and also capable of withstanding corrosion incidental to the coking processes as well as that of salts used in the coking bath. In the form of apparatus shown, a coking bath is placed in the chamber 20 between the outer casing 15 and the inner casing 16, while coal or similar material being carbonized is placed within the inner casing 16, as will hereinafter more fully appear. The base member 17 has an opening 21 at its lower end of sufficient diameter to receive the inner casing 16 therein, in the form shown said casing having threaded engagement with said opening. Closure means are provided for this opening, in the form shown this means comprising a door 22 carried on an arm 23 supported in bearings 24 on the lower face of the member 17 and operable by a shaft 25 for swinging the door 22 into open or closed position with respect to the opening 21, as will hereinafter more fully appear. The outer casing 15 is suitably supported by the member 17 in concentric relation with the inner casing 16, in the form shown the supporting means comprising an annular shoulder 27 in which the outer casing 15 has threaded engagement. An annular passage 29 is also provided within the base 17 for permitting circulation of water or other cooling agent to keep said base cool, and also to assist in freezing or solidify-

ing the bath at the lower joints to prevent leakage at these points.

The cap member 18 at the top of the container is provided with an opening 30 within 5 which the inner casing 16 is secured and having a cover 31 fitting therein. Means for securing the cover in place comprises a link 32 having the cover 31 hinged at 33 centrally thereof, said link being pivotally connected 10 at one end to a lug 34 by means of a connecting member 35, and at the opposite end by a suitable detachable connection, as for instance, by a U-shaped yoke 36 pivoted at 37 to a lug 38 on the cap member and adapted 15 to be swung over the free outer end of the link 32. An opening is provided adjacent the upper end of the inner coke containing sleeve for permitting the escape of volatile gases from the container. In the form shown, 20 this opening comprises a laterally extending passage or duct 40 through one side wall of the cap 18. The bath salts may be fed or replenished to the chamber 20 through plug 41 in cap 18.

Referring again to Figure 2, it will be observed that a plurality of coke containers 12 are arranged in vertical position parallel with each other, each of said containers being in a compartment 45 formed between side walls 46—46 of fire resisting brick, or the like, and separated from each other by transversely disposed walls 46a—46a. Heat is supplied to the battery through a fire-box 47 preferably arranged along one side of the battery. 35 The heat may be supplied by any suitable source, as for instance, gas burners 44, discharging through orifices 48 at the lower end of the fire-box 47. The heat passes over suitable baffles 49, 49 arranged to equalize the 40 distribution thereof through ports 50—50 near the bottom of the side wall 46 opposite each of the chambers 45 in which the coking elements are located. Said chambers are preferably of such width so that the coking 45 units 12—12 engage the intervening partitions 46a—46a at opposite sides thereof so that the heating gases pass upwardly in the chambers 45 and through ports 51—51 adjacent the upper end of said containers and 50 communicate with the opposite or inner side of the chambers 45. From thence the gases pass downwardly along the inner side of the containers and are discharged through ports 52—52 communicating with a lateral discharge passage 53 extending centrally of the entire coking unit and forming a common discharge passage for all of the units, as shown in Figure 2. In the preferred form shown, I also provide a series of smaller inlet passages 54 communicating from the upper end of the fire-box 47 to the chambers 45, these passages forming an auxiliary inlet for gases opposite the transverse passages 51 so as to raise the temperature of the partially cooled gases 55 which has passed upwardly from ports 50,

and thus tending to equalize the temperature on opposite sides of the carbonizing containers.

In operation, the chamber 20 surrounding each of the coking containing elements is 70 filled with fusible salts suitable for forming a bath. As an illustrative embodiment of the method of my invention, I employ a mixture of 72½% of calcium chloride with 75 27½% of sodium chloride when dry, this being the eutectic mixture of these salts, that is to say, a mixture which is fusible at the lowest temperature or approximately 800° F. and may be advantageously operated to coke coal at a temperature below 1200° F. 80

Having described one of the carbonizing units, I will now describe the entire apparatus.

The structure as a whole comprises a plurality of vertical side walls 55—55 and end 85 walls 56 and 57 made of fire-brick or the like. The smothering pits 11 (along which may run tracks for cars, not shown) form the lower part of the structure. The smothering pits receive the charge after it is coked 90 and prevents it from burning or being ignited. Supported on the brick-work 55, 56 and 57 by suitable cross-members 60 are a plurality of batteries of five carbonizing elements 12—12 as previously described, the base members 17 of said containers being supported on the cross-members 60, and pillars 61 and arches 62 supporting the upper carbonizing structure and the intermediate brick-work walls. At the outer sides of each 100 battery of five coke containers are the fire-boxes 47—47, in this instance four such units being shown with their respective fireboxes. Any suitable source of heat may be used such as gas burners 44, controlled by thermostatic regulation from the fused salt to maintain the baths at the desired temperature, if desired. Such thermostatic regulating means are well known and are not shown herein. The passage of the gas from the fire-boxes through the carbonizing units has already been described in connection with one 110 of the units, and all of the units have a common discharge passage 53 through which the exhausted gases pass and through a common enlarged opening 67 at one end of the structure. The gas-escape ducts 40 at the top of the carbonizing elements 12 are connected to common lead-off pipes 43. The shafts 25, 25 controlling the discharge doors 22 of the 120 carbonizing elements 12, extend to the outside of the structure, and are operated by suitable ratchet devices 25a, 25a and handle 25b.

In operation the space between the double walls of each of the outer casings 15 and inner casings 16 being filled with fusible salt, the bath is brought to and maintained at the proper temperature, preferably between 1050° and 1200° F., depending upon 130

the grade of coal to be used, it being understood that one of the principal features of the process is the provision of means for carbonization at relatively low temperatures. 5 The doors 22 being closed, the covers 31 being removed, the coke containers are filled with coal from a traveling hopper or otherwise. The covers 31 being replaced and secured, carbonizing starts and continues until 10 the charge is completely carbonized.

At the closing of the carbonizing operation, the doors 22 are opened and the carbonized product drops into the smothering pit, its discharge being facilitated if desired 15 by a slight divergence of the inner walls of the inner container 15 toward the bottom. Under ordinary circumstances, however, when the carbonizing operation is properly completed, with most coals, the carbonized product shrinks throughout its entire length so as to be readily discharged by gravity. The doors 22 are then closed and the operation repeated. The carbonized product is removed from the smothering pit 11 at convenient times. 25

It will be observed that the base plate 17 is located below the zone of maximum heat produced through the passageways or chambers 45, and at the upper end of the smothering or cooling pits 11. With a eutectic saline bath, such as described herein, it will be understood that leakage which otherwise is likely to occur at the lower part of the carbonizing elements is prevented due to the fact that a bath of this character will be frozen or solidified as soon as it reaches the cooler outside air.

I claim as my invention:

1. In apparatus of the character described, a plurality of upright carbonizing elements, each comprising two concentric tubular members having their side walls spaced apart and closed at the lower end to form a bath chamber and containing a saline heating bath, the inner member having removable closures at the top and bottom thereof, and means for applying heat externally of said elements comprising a supporting structure having upright division walls forming separate heat chambers for each of said elements intermediate the upper and lower ends thereof. 45

2. In apparatus of the character described, a plurality of upright carbonizing elements, each comprising two concentric tubular members having their side walls spaced apart and closed at the lower end to form a bath chamber and containing a saline heating bath, the inner member having removable closures at the top and bottom thereof, and means for applying heat externally of said elements, comprising a supporting structure having upright division walls forming separate heat chambers for each of said elements intermediate the upper and lower ends thereof, 55 and permitting circulation from a common

heating chamber upwardly on one side and downwardly on the opposite side of said elements.

3. In apparatus of the character described, a plurality of upright carbonizing elements, each comprising two concentric tubular members having their side walls spaced apart and closed at the lower end to form a bath chamber and containing a saline heating bath, the inner member having removable closures at the top and bottom thereof, 70 means for applying heat externally of said elements comprising a supporting structure having upright division walls forming separating heat chambers for each of said elements intermediate the upper and lower ends thereof, permitting circulation from a common heating chamber upwardly on one side and downwardly on the opposite side of said elements, 75 and baffle means in said common heating chamber affording equalization of heat in the several chambers served thereby. 80

4. In apparatus of the character described, an upright carbonizing element, comprising two concentric tubular members having their side walls spaced apart and containing a saline heating bath, a base member supporting the lower ends of said members and closing the lower end of the space between them, and means for applying heat externally 90 of said element, said base member extending downwardly beyond said heating means whereby escape of said saline bath may be prevented by solidification of the latter in the zone below said heating means. 95

5. In apparatus of the character described and in combination, a heat generating element, a plurality of heating chambers adjacent said heat generating element and communicating therewith, a plurality of double walled containers in said heating chamber comprising two tubular members having their side walls spaced apart to form a bath chamber with the upper and lower ends thereof projecting beyond said heating chamber, 105 said bath chamber containing a saline heating bath and means for causing gases from the heat generating element to pass upwardly on one side and downwardly on the other side of each container, and auxiliary ingress means 110 from said heat generating element to each of said heating chambers adjacent the top thereof. 115

Signed at Clinton this 11th day of July, 1925.

JOHN MITCHELL.
